The ornamental design for a syringe plunger, as shown and described.

DESCRIPTION

FIG. 1 is a top perspective view of a syringe plunger in accordance with the present invention.

FIG. 2 is a front elevation view thereof;

FIG. 3 is a rear elevation view thereof;

FIG. 4 is a top plan view thereof;

FIG. 5 is a bottom plan view thereof;

FIG. 6 is a right-side elevation view thereof; and,

FIG. 7 is a left-side elevation view thereof.

Portions of the syringe plunger shown in dashed lines in FIG. 1 and FIG. 4 depict unclaimed portions of the syringe plunger that are included for environmental purposes only.
